UNITED STATES PATENT OFFICE

RICHARD E. BRUNS, OF CHICAGO, ILLINOIS.

MACHINE FOR FEEDING BOTTLES TO AND FOR OPERATING BOTTLE-CAPPING MACHINES.

1,116,556.

Specification of Letters Patent. Patented Nov. 10, 1914.

Application filed July 28, 1913. Serial No. 781,514.

To all whom it may concern:

Be it known that I, RICHARD E. BRUNS, a citizen of the United States, residing at Chicago, in the county of Cook and State of Illinois, have invented certain new and useful Improvements in Machines for Feeding Bottles to and for Operating Bottle-Capping Machines, of which the following is a specification.

10 My invention relates to a machine for feeding bottles to and for operating a bottle capping machine.

In commercial practice bottle capping machines are now generally fed by hand, an operator placing the bottle in proper position with respect to the capping mechanism, operating a foot treadle which sets in motion the automatic capping mechanism, and manually removing the bottle from the capping machine when the sealing has been completed.

My invention provides a mechanism for automatically performing all of the operations above referred to, which are now performed by a human operative.

Heretofore effort has been made to provide for the automatic feeding of bottles to capping machines by instrumentalities controlled or operated from the capping machine, but inherent difficulties of grave nature have been encountered in such attempts owing, among other things, to the troubles involved in working the feeding mechanism from the instrumentalities which are present in the successful forms of commercial capping machines, to the disturbance of the parts of the capper, and to other difficulties. These difficulties I overcome, primarily, by the construction of the feeding mechanism

40 appropriately to actuate and control the operation of the capping machine without any change whatever in the capper, insuring proper coördination of the operations of the feeding and capping machines, not interfering with or varying in any way the operation of the capping machine and making my feeding machine available, with mere adaptation of size, proportion, and mechanical details, for the operation of any commercial capping machine construction.

Specific objects sought and advantages attained by my invention will be apparent to those skilled in the art from the following

description taken in conjunction with the accompanying drawings, in which—

Figure 1 is a central vertical section, with parts in elevation, of an embodiment of my invention shown in its coöperative relation to parts of a capping machine indicated by dotted lines. Fig. 2 is a side view of the machine. Fig. 3 is an opposite side view of the machine. Fig. 4 is a sectional detail on line 4—4 of Figs. 1 and 3. Fig. 5 is a plan view of the machine. Figs. 6 and 7 are details, in plan and vertical sections respectively, of a take-up. Fig. 8 is a sectional detail on line 8—8 of Fig. 5. Fig. 9 is an enlarged detail seen on line 9—9 of Fig. 1; and Fig. 10 is an under side view of the ratchet plate as seen from line 10—10 of Fig. 1.

The capper C has a treadle t for usual foot power operation, depression of said treadle causing the capper automatically to perform its functions, with which those skilled in the art are familiar.

In the specific construction of my machine shown for illustration, the frame 15 provides a base chamber 16 having an opening 17 to receive the treadle t, so that said treadle may be operated by the treadle actuator 18 which, in this particular instance, is a vertical plunger extending through the horizontal wall 19 of the frame and normally raised by a spring 20 suitably secured to the frame. Above the horizontal wall 19 the frame 15 provides a chamber 21 for gearing mechanism, to be described, closable by door 22 and from the outer side of the housing there extends upward the arm 23 overhanging to provide the central bearing head 24.

In the specific construction shown the bottles are handled by the coöperation of a table, conveyor, carrier, and guide.

The arcuate table 25 extends inwardly or toward the capping machine to coöperate with and supplement the bottle receiving base of the capping machine, and its perimeter is recessed as at 26 to embrace the appropriate bottle-receiving base-portion of the capping machine. Vertical adjustment for the table 25 is provided that its position may be accommodated with the adjusted positions of the associated parts of the capping machine for proper operation on bottles of

different heights, and to this end the table is secured to a longitudinal yoke or frame 27 the central portion of which has vertical slot connection with clamping bolts 28 extending into the bearing head 24, a projection 27' on the yoke 27 extending into a suitable vertical recess 24' in said bearing head and engaging a vertical adjusting screw 29 carried by said bearing head.

10 The conveyer 30 is preferably an endless belt the upper or active course of which passes across a chord of the table in a recess 25' (to bring its upper surface flush with the table surface) and which extends 15 longitudinally on both sides of the arcuate table, over a belt platform 31 (which may be an extension of the table) so that the same belt may act both to convey the bottles into and to remove them from the range of 20 operation of the carrier. The platforms 31 carry at their ends pulleys 32 mounted in longitudinally adjustable hangers 32', and the belt at its lower course runs under a driver-pulley 33 carried by the transverse 25 shaft 34 which is mounted in a suitable bearing 35 supported on the arm 23. A suitable belt slack take-up is provided by mounting on the bearing 35 a pivoted arm 36 which at one end bears the idle roller 37 30 operating against the under side of the belt to tighten it around the driver 33 and at its opposite extremity bears the adjustable tension weight 38.

The carrier 40 is keyed to the vertical 35 shaft 41 which extends through suitable bearings in the bearing head 24 and base wall 19 and acts against the thrust bearings 42-42'. This carrier 40 may be a spider 40 having its rim contorted to form bottle-receiving pockets 43 of suitable vertical extent to insure proper coöperation with the bottles whatever may be the adjustment of the table 30. The carrier is shown as of a ten-pocket construction and the remaining 45 parts of the machine are adapted for this number as will be understood without further reference to number. I prefer that the rim 44, preferably of substantially uniform thickness, should extend vertically below 50 the spider arms 45 so that the convex curved surface at the back of each pocket may, in the rotation of the carrier, coact with a detent 46 which, as shown in Figs. 5, 6 and 7, is pivoted on a suitable frame member and 55 acted upon by a spring 47 so that its eccentrically formed perimeter, edged with a projecting frictional rib 48, may permit the bottle-receiving pockets to pass freely in the direction of intended rotation of the carrier 60 but may automatically prevent back lash or retrograde movement of the carrier, the detent 46, of course, being so positioned that it will perform its function each time the carrier comes to rest after one of its intermittent movements, to be described;

The guide 50 for coöperation with the carrier extends, preferably concentrically with the carrier, above the periphery of the table around the arc spanned by the belt chord and is preferably flexible throughout that extent. 70

Specifically I provide upper and lower rails 51 of flexible metal bands supported at the extremities of their arc on posts 52 and free from support throughout the arc which substantially conforms with the carrier. This guide 50 may be extended along the inner side of the belt platforms 31 to both ends thereof, additional posts 52 being provided as required. Also I prefer that complementary rails 50' be provided on the outer side of the platforms, the rail at the entrance end of the structure having its extremity which is nearest the carrier deflected inwardly, as at 54, so that the bottles are given a lead in the proper direction as they leave the guiding influence of rail 50' and are acted on by the carrier 40. 80

The driving mechanism is arranged to impart intermittent timed motion to the carrier shaft 41 and intermittently to depress the actuator 18 in definite timed relation, both actions timed with respect to the main shaft. The main shaft 60 is horizontally mounted in bearings provided in the bracket 61 and the side of the frame, and carries pulleys 62. A chain 63 may be exteriorly provided to connect suitable sprockets on shafts 60 and 34 for continuously driving the belt. Within the frame 100 the shaft 60 carries a beveled pinion 64 coöperating with a beveled gear wheel 65, loosely surrounding the shaft 41. The gear wheel carries on its under surface one or more cams 66 operating to depress the actuator 18 at regular intervals in the rotation of the gear wheel. 105

The driving connection between the main shaft and the carrier shaft 41 is frictionally effected, there being preferably means constantly tending frictionally to drive the shaft 41, and means, timed by the operation of the main shaft, for preventing rotation of shaft 41 at intervals. Specifically, 110 70 indicates a disk rotatable with, but axially movable with respect to, the shaft 41 through the feather and spline connection 71. A nut 72, screwed on a threaded portion of shaft 41, bears upon spring 73 which constantly forces the disk toward the gear 65. 115 The confronting surfaces of the disk and gear are equipped with frictional bodies 65' and 70' between which may be interposed the friction plate 74. These parts exert a constant tendency to cause rotation of the 120 shaft 41 in harmony with the rotation of the main shaft 60.

The under side of disk 70, radially beyond the friction bodies 70' has crown ratchet teeth 75 (Fig. 10) against which acts a 125

pivoted pawl 76 carried by a shaft 77 which is acted upon by a spring 78 tending to yieldingly hold said pawl in position to prevent rotation of the disk. The number of teeth of the disk ratchet coincides with the number of pockets of the carrier so that every time the pawl is disengaged from the disk, the disk rotates to the extent of one pocket of the carrier, advancing said carrier 10 step by step. One or more lugs 79 are provided on the gear wheel 65 to act upon the tail of the pawl to throw it out of engagement with the ratchet teeth of disk 75 each such lug 79 being properly related to a corner 15 responding one of the cams 66 on the under side of the gear so that retraction of the pawl to permit rotation of the carrier shaft 41 invariably will be in proper time relation with the operation of actuator 18.

20 In brief résumé of the operation:—The power shaft constantly rotates the gear 65 and constantly drives the bottle carrying belt. The frictional connection between carrier shaft 41 and gear 65 tends constantly 25 to rotate said carrier shaft and its bottle carrier 40, but rotation of the latter is restrained by pawl 76, acting on disk 75, the pawl being thrown out from engagement with the disk 75 at intervals definitely timed 30 with relation to the depression of the actuator 18 by the relation of the actuator cam 66 on the one side of said gear and the pawl actuating lug 79 on the other side of said gear. Whenever the pawl is thrown out of 35 engagement with the ratchet teeth on the disk 70 the frictional connection between gear 65 and disk 70 rotates the shaft 41 one step, until the pawl 76 engages the next tooth of the ratchet, each step presenting a 40 successive pocket of the carrier 40 to the capping machine. The frictional gearing insures operation of the carrier smoothly, and its starting without a disadvantageous jar. The positive stopping of the carrier rotation, which might otherwise cause a slight back-lash, is compensated for by the provision of the detent 46 which automatically 45 operates to prevent any retrograde movement of the carrier, said detent performing its holding function in the manner clearly 50 illustrated in Fig. 5. The constantly moving belt 30 carries the bottles in a row to the carrier and one at a time they are received in the carrier pockets, each bottle being 55 moved in an arc across the stationary table to the appropriate part of the capping machine, and maintained in that position by the dwell of the carrier at the time said capping machine performs its functional operation. Each bottle is then carried from 60 the capping machine back to and across the table on to the belt 30 and is thus transported to the end of the machine for delivery.

65 While I have herein described in some de-

tail a particular embodiment of my invention involving many advantageous features in detail, some of which I may claim for their joint and several advantages, it will be apparent to those skilled in the art that many changes in the construction of my machine might be made without departure from the spirit of my invention and within the scope of the appended claims.

Having described my invention, what I claim is:

1. In a machine for feeding and operating an automatic bottle capper, the combination of a frame, a main shaft, an actuator adapted for operation of a capper treadle, a rotating part driven by said main shaft and operating said actuator, a rotary carrier, a shaft for said carrier, means to effect frictional connection between said rotary part and said carrier shaft, and means for intermittently preventing rotation of said carrier shaft.

2. In a machine for feeding and operating an automatic bottle capping machine, the combination of a frame, a main shaft, a carrier, a carrier shaft, a gear driven from the main shaft loosely surrounding the carrier shaft, friction means on the carrier shaft for coöperation with said gear, a detent for preventing rotation of the carrier shaft, means on said gear for controlling said detent, an actuator adapted to operate a capping machine treadle and means operated by said gear for operating the actuator.

3. In a bottle feeding machine, the combination of a rotatable bottle carrier, a carrier shaft, a main shaft, a gear constantly driven from said main shaft, a friction disk carried by the carrier shaft confronting said gear, means for maintaining constant frictional engagement between said disk and gear, means for positively restraining said disk against rotation, and means carried by the gear for intermittently actuating said restraining means to remove the restraint against the disk rotation.

4. In a bottle feeding machine, the combination of a bottle carrier, a carrier shaft, a main shaft, a gear driven by said main shaft loosely surrounding the carrier shaft, a disk rotatively carried by said carrier shaft, means for causing constant frictional engagement between said disk and gear, a detent coöperating with said gear to prevent rotation of the disk, and means on said gear for operating said detent to free the disk to be frictionally driven by the gear.

5. In a machine of the character described, a bottle carrier having a rim deflected inwardly at intervals to form pockets, means for intermittently moving said carrier rotatively to present its pockets successively to a predetermined point, and a pivoted detent having an eccentric acting end coöperating with the exterior curved

surfaces of the rim pockets to prevent retrograde movement of the carrier.

6. In a machine for feeding and operating an automatic bottle capper, the combination 5 of a frame, a main shaft, a carrier shaft, a gear driven from the main shaft rotatable about the carrier shaft, an axially movable disk rotatively secured to the carrier shaft adjacent the said gear and spring pressed 10 into frictional engagement therewith, a detent for preventing rotation of the said disk, means on said gear controlling said detent, an actuator adapted to operate a capping machine treadle, and means operated by 15 said gear for operating the actuator.

7. In a machine for feeding and operating an automatic bottle capper, the combination 20 of a frame, a main shaft, a carrier shaft, a gear driven from the main shaft rotatable about the carrier shaft, an axially movable disk, rotatively secured to the carrier shaft, adjacent the said gear and spring pressed 25 into frictional engagement therewith, ratchet teeth near the periphery of said disk upon the face adjacent the gear, a ratchet adapted to coöperate with said teeth for preventing rotation of the carrier shaft, means on said gear for controlling the operation 30 of said ratchet, an actuator adapted to operate the capping machine treadle, and means operated by said gear for operating the actuator.

8. In a machine for feeding and operating an automatic bottle capper, the combination 35 of a frame, a main shaft, a carrier shaft, a

gear driven from the main shaft rotatable about the carrier shaft, an axially movable disk rotatively secured to the carrier shaft adjacent said gear and pressed into frictional engagement therewith, ratchet teeth 40 upon the said disk, a pawl carried by said frame and spring pressed into engagement with the ratchet to prevent rotation of the carrier shaft, means operated in timed relation with said main shaft for releasing said 45 ratchet, an actuator adapted to operate a capping machine treadle and means operated in timed relation with said main shaft for operating the actuator.

9. In a machine for feeding and operating 50 an automatic bottle capper, the combination of a frame, a main shaft, a vertical carrier shaft, a gear driven from the main shaft, rotatable about the carrier shaft, an axially movable disk rotatively secured to the carrier shaft above the said gear, and spring 55 pressed into frictional engagement therewith, a detent positioned between said disk and gear for preventing rotation of the disk, means on said gear for controlling said detent, an actuator adapted to operate a capping machine treadle and means operated 60 by said gear for operating the actuator.

In testimony whereof I hereunto set my hand in the presence of two witnesses.

RICHARD E. BRUNS.
